UNITED STATES PATENT OFFICE.

THOMAS SIMMONS, OF HARTFORD, CONNECTICUT, ASSIGNOR OF ONE-THIRD
TO HIRAM J. WIERS, OF SAME PLACE.

TRUSS.

SPECIFICATION forming part of Letters Patent No. 268,951, dated December 12, 1882.

Application filed August 15, 1882. (Model.)

To all whom it may concern:

Be it known that I, THOMAS SIMMONS, a citizen of the United States, residing at Hartford, in the county of Hartford and State of Connecticut, have invented certain new and useful Improvements in Trusses; and I do hereby declare that the following is a full, clear, and exact description of the same, reference being had to the annexed drawings, making a part of this specification, and to the letters and figures of reference marked thereon.

Figure 1 of the drawings is a perspective view of my invention; Fig. 2, an elevation of the body or inner side of the pad; Fig. 3, a similar view of the outer side of the same; Fig. 4, a detail sectional view of the pad; Fig. 5, a detail view of the adjusting-plate and portion of the belt; Figs. 6 and 7, detail views of the connecting eye-pieces, and Fig. 8 a detail view of the belt-support.

This invention relates to certain new and useful improvements in trusses for the support of hernia, the objects thereof being to provide such a truss as will be light and simple in its construction, readily applied, and quickly adjusted to the body, and from the peculiar shape of the pads and their attachments the hernia may be held in place after reduction with a gentle pressure, thus giving ease and comfort to the wearer. These objects I attain by the construction substantially as shown in the drawings, and hereinafter described.

In the accompanying drawings, A represents a support formed of a vertical piece, *a*, and right-angle pieces *b c*, of metal or other suitable material. To the lower right-angle piece, *c*, of this support is affixed a belt, B, which is intended to fit snugly to the hips of the wearer, the ends thereof connecting with a plate, C, which holds in place the pads D. These pads D are made of wood, hard rubber, celluloid, or other suitable material, of an elliptical shape, having their lower extremities upon their interior faces raised in the form of ribs *d*, as illustrated by Figs. 2 and 4 of the drawings, to exert an inwardly-yielding pressure upon the hernia, to accommodate it to the movements of the body, this pressure being similar to that exerted by the fingers of the human hand, by which it is well known that hernia of most

kinds may be readily supported, especially that known as "inguinal" hernia. These pads are affixed to plates E, provided with brackets *e*, in which works a thumb-screw, *f*, which engages with perforations *g* in the plate C to adjust the pads thereon, the ends of the said thumb-screws sinking into depressions *h* in the pads, thus admitting of their being screwed up close to the brackets upon the plates E, out of the way. The plate C is also provided at its ends with a series of eyes, *i*, engaging with buttons or hooks *k* to loosen or tighten the belt.

To the back of the belt B are suitably connected straps F, which pass between the limbs of the wearer and connect with the pads by means of eye-pieces G, Fig. 6, secured thereto, said eye-pieces passing between the plate E and the bracket *e* thereon, and held in place by the thumb-screw *f*, passing through the eye *l* and engaging with the plate C, as before described.

To the right-angle piece *b* of the support A is affixed a belt, H, which fits just above the pelvic region of the wearer, and extends around and connects with the pads by means of eye-pieces I, Fig. 7, connected to the ends of the said belt and provided with elongated eyes *m*, which couple upon buttons or hooks *n* upon the plates E of the pads at their upper ends.

By constructing a truss in the manner described the pads bear upon the hernia with an upwardly-yielding pressure, keeping it in its place and supporting the abdomen to relieve the rupture from the weight of the intestines.

From the arrangement of the belts and straps in conjunction with the perforated plate having a series of eyes upon its ends the truss is readily adjusted to the body of the wearer and the pads to the exact location of the hernia.

Having now fully described my invention, what I claim as new, and desire to secure by Letters Patent, is—

1. In a truss, the pads D, adjustably connected to the plate C, which in turn is adjustably connected to the ends of the belt B, in combination with the belt H, straps F, and the support A, substantially as and for the purpose set forth.

2. In a truss, the support A, formed of a vertical piece, *a*, and right-angle pieces *b c*, in

combination with the upper belt, H, and lower belt, B, substantially as and for the purpose set forth.

3. In a truss, the support A, belts B H, and 5 straps F, in combination with the plate C and pads D, all arranged to operate in the manner described, and for the purpose specified.

In testimony that I claim the above I have hereunto subscribed my name in the presence of two witnesses.

THOMAS SIMMONS.
